FIG. 1 is a perspective view of a stackable bulk food display module showing my new design;
FIG. 2 is a front elevational view thereof;
FIG. 3 is a top plan view thereof;
FIG. 4 is a left side elevational view the right side being a mirror image thereof;
FIG. 5 is a bottom plan view thereof; and
FIG. 6 is a front elevational view showing the module as it would appear in an environmental setting. The broken line showing of portions of other modules is for illustrative purposes only and forms no part of the claimed design.

FIG. 1

FIG. 4

FIG. 2

FIG. 5

FIG. 3
